CLAIM

The ornamental design for a wind cage for a decorative-flame burner, as shown and described.

DESCRIPTION

FIG. 1 is a perspective view of a wind cage for a decorative-flame burner.

FIG. 2 is a front view of the wind cage of FIG. 1.

FIG. 3 is a rear view of the wind cage of FIG. 1.

FIG. 4 is a right side view of the wind cage of FIG. 1.

FIG. 5 is a left side view of the wind cage of FIG. 1.

FIG. 6 is a top view of the wind cage of FIG. 1; and,

FIG. 7 is a bottom view of the wind cage of FIG. 1.

The broken lines in the Figures are directed to unclaimed subject matter of the wind cage for a decorative-flame burner. The portions of the wind cage for a decorative-flame burner shown in broken lines form no part of the claimed design. The dash-dot broken line in FIG. 7 depicts the bounds of the claim and forms no part of the claim.

1 Claim, 7 Drawing Sheets
